ABSTRACT: A high-voltage electrical insulator of synthetic plastics material having a predetermined electrical conductance to inhibit discharges of the order of 7 milliamperes and less but to permit larger current discharges. Preferably said conductance is provided by surface conductance and preferably it is discharges of 5 milliamperes and less which are inhibited.

1
**HIGH-VOLTAGE ELECTRICAL INSULATOR HAVING A
PREDETERMINED SURFACE CONDUCTANCE**

This invention relates to high voltage electrical insulators suitable for outdoor use. Such insulators as widely used today are of glazed porcelain and are perfectly satisfactory in operation. However, recent interest has been directed to the use of plastics materials for high-voltage insulators, for example, glass-fiber reinforced plastics materials, which have certain advantages over glazed porcelain.

The use of high-voltage plastics insulators outdoors is at the present time seriously restricted by the phenomena known as tracking, i.e. carbonization of the surface of the insulator by surface electrical discharges, which results in a permanent degradation of the insulating properties of the insulator. It is the object of this invention to prevent such tracking.

The invention is based on the discovery that if surface electrical discharges of the order of 7 milliamperes and less are inhibited there is no significant tracking; hence higher magnitude surface electrical discharges can be permitted. Accordingly the invention provides an insulator of synthetic plastics material having a continuous coating on its outer surface to produce a surface such that the plastics insulator has a predetermined electrical conductance so as to inhibit discharges of the order of 7 milliamperes and less.

Preferably said electrical conductance is such as to inhibit discharges of 5 milliamperes and less but to permit higher current discharges.

Surface electric discharge of an insulator is caused by the rapid drying-out of wet pollution on its surface by the leakage current flowing through the pollution. In the case where, in accordance with the invention, surface conductance is provided on the insulator it can be shown that surface discharges will not occur unless the current through the pollution exceeds a limiting value according to the following expression:

$$\frac{V}{x} = \frac{E}{L} \frac{i_p}{i_s}$$

where:

V/x is the voltage stress (volts per centimeter) at which the surface breaks down; this means that surface discharge cannot take place at a lower stress,

E is the voltage across the insulator,

L is the minimum distance along the surface of the insulator between its ends,

i_p is the minimum leakage current through the pollution at which discharge is to be permitted,

i_s is the current that normally flows by reason of the surface conductance of the insulator when the insulator is dry.

Since in accordance with the invention the value of i_s will be given by a value of the order of 7 milliamperes the surface conductance can be determined by applying Ohms law ($K=I/E$) to the calculated value of $'g'$.

- 5 If for example the critical value for V/x is 17.5 kv./cm., E is 35 kv., (peak value of 25 kv. AC supply) L is 1 meter and $'p$ is greater than 5 ma., then the surface conductance provided in the insulator will have to provide a leakage current $'g'$ of about 100 A. and the conductance would be about .000285 μ mho.
- 10 If the surface conductance of the insulator increases (i.e. the resistivity decreases) with increasing voltage stress, for example, by using known materials in the coating whose ohmic resistance decreases with an increase in voltage stress, then the steady state leakage can be reduced. Thus if the surface resistivity for a voltage stress E/L is 10 times greater than that at the breakdown stress V/x then the steady state current leakage through the dry insulator can be reduced say from 100 to 10 μ A. The surface conductance of the insulator may be provided by a coating of flexibilized resin intimately mixed with
- 15 20 antimony doped tin oxide powder, the coating being cured on the insulator.

We claim:

1. A high-voltage insulator comprising a synthetic plastic body and a continuous coating of a conductive material on the surface thereof, said coating having a thickness and being of a material to inhibit discharge of electrical currents therethrough below about 7 mA while passing currents above said 7 mA.
- 25 2. An insulator in accordance with claim 1 wherein i_s is calculated from the following formula:

$$\frac{V}{x} = \frac{E}{L} \times \frac{i_p}{i_s}$$

35 where:

V/x is the voltage stress (volts per centimeter) at which the surface breaks down; this means that surface discharge cannot take place at a lower stress,

E is the voltage across the insulator,

40 L is the minimum distance along the insulator between its ends,

i_p is the minimum current of the permitted discharge and is greater than 7 mA,

45 i_s is the current that normally flows through the surface of the insulator when the insulator is dry, and the surface conductance is calculated from the value of i_s using Ohms law.

3. An insulator in accordance with claim 1 wherein the surface electrical conductance increases with increasing voltage stress.
